UNITED STATES PATENT OFFICE.

FREDERICK A. STAFFORD, OF CHARITON, IOWA.

TAMPER.

1,085,505.

Specification of Letters Patent.

Patented Jan. 27, 1914.

Application filed January 20, 1913. Serial No. 743,008.

To all whom it may concern:

Be it known that I, FREDERICK A. STAFFORD, a citizen of the United States, and a resident of Chariton, in the county of Lucas and State of Iowa, have invented certain new and useful Improvements in Tamers; and I do hereby declare that the following is a full, clear, and exact description thereof, reference being had to the accompanying drawings, and to the characters of reference marked thereon, which form a part of this specification.

This invention relates to a novel tamper for tamping concrete and the like, and refers more specifically to a novel means of connecting the handle to the tamping plate so arranged as to permit the plate to be deflected out of the line of the handle, so that the tamping plate may adjust itself to an inequality in the surface being tamped without danger of breaking the handle or injuring the user of the device, and may adjust itself to surfaces disposed at an oblique angle to the handle.

The invention has for its object to otherwise improve and simplify the connection between the handle and tamper plate, and the invention consists in the matters hereinafter set forth and more particularly pointed out in the appended claims.

In the drawings: Figure 1 is a perspective view of the tamper embodying my invention. Fig. 2 is an axial section of the flexible connection between the handle and the tamper plate. Fig. 3 is a side elevation showing the use of the flexible connection between the handle and the tamper plate.

In the drawings, 10 designates the tamper plate, 11 the handle and 12 designates, as a whole, the flexible connection between said plate and handle. The flexible connection between the plate and handle may be variously constructed to permit the plate to be turned or deflected out of line with the handle. It preferably embraces a resilient flexible member constructed and arranged to restore the tamper plate to its normal position when unrestrained, so that the plate will always be in position for proper presentation to the plane of the bed of concrete or other work. A preferred construction of such connection which I have found efficient in practice consists of a closely

wound coil of resilient wire of cylindric contour. As a means of connecting the coil with the tamper plate and handle, the said plate may be provided with an upstanding screw-threaded stud 14, the thread of which is of a pitch to engage the turns of the coil, and the lower end 15 of the handle may be likewise screw-threaded to engage into the outer end of said coil. The lower end of the handle terminates short of the stud 14, being spaced therefrom by a number of turns of the coil, so as to give to the flexible connection considerable degree of flexibility between the handle and the stud.

In order that the flexible coil connection may be readily screwed off the tamper plate stud, and that the lower end of the handle may be screwed out of the coil, the terminals of the coil are extended beyond the contour proper of the coil to provide releasing ends 10, 17 to facilitate the removal of the coil from said stud and the handle from the coil. The coil may be readily screwed into the tamper plate stud and the handle readily screwed into the coil, inasmuch as the action of the parts at this time has a tendency to open the coil and readily admit the screw-threaded assembling. When turned in the other direction, however, either the coil on the stud 14, or the handle in the coil, the friction between the parts has a tendency to close the coil and, therefore, bind the coil on the parts so that the coil may not be released therefrom. However, by pressing the terminal ends 16, 17 of the coil in the direction to open the turns of the coil, such binding or clamping action is not manifested, and the parts are free for ready dismemberment.

The flexible connection permits the tamper plate to adjust itself to inequalities in the surface being tamped without throwing a strain on the handle tending to break the handle or sprain the wrist of the user, such as occurs in rigid handle tampers. Moreover, should the tamper plate be presented to the tamped surface at an oblique angle, the flexible connection described permits the plate to adjust itself to the plane of the work, and without a tendency to dig up or displace the concrete work. The resilient flexible connection such as the coil spring shown, insures that the tamper plate will resume its normal position when lifted from

the work so that its face will be in proper position for subsequent presentation to the work.

I claim as my invention:—

- 5 1. A tamper comprising a tamper plate, a handle and a closely wound spring wire coil connecting the handle and the plate.
- 2. A tamper comprising a tamper plate, a handle and a closely wound spring wire
- 10 coil, said plate being provided with a screw-threaded stud for screw-threaded engagement with one end of the coil, and the handle being screw-threaded into the other end of the coil.

3. A tamper comprising a tamper plate, ¹⁵ a handle and a closely wound spring wire coil connecting the handle and plate, the terminals of the wire extending beyond the coil to constitute releasing ends.

In testimony that I claim the foregoing ²⁰ as my invention I affix my signature in the presence of two witnesses, this 17th day of January, A. D. 1913.

FREDERICK A. STAFFORD.
